ROBERTO GALEAZZI, OF MUGGIANO, SPEZIA, ITALY

RESISTANT SUBMARINE HULL OR THE LIKE

Application filed September 22, 1927, Serial No. 221,275, and in Italy October 25, 1926.

My invention relates generally to resistant shells or casings of elongated receptacles subjected to either external or internal pressure, and aims at providing a shell which will 5 practically act as a sphere throughout its length. My invention more particularly relates to the resistant hulls of submarines, and its particular object is to provide a resistant submarine hull consisting of elements practically acting as spheres as regards its resistance to the external pressure.

It is known that by a cylinder having R as the radius, and being subjected to a pressure P , either external or internal, the elementary stress on the cylinder wall is $\frac{PR}{2}$, while by a sphere also having R as the radius and being subjected to a pressure P , the stress is

$$20 \quad \frac{PR}{2}.$$

This substantially means that the sphere shell may be made of a thickness equal to 25 half the thickness of the cylinder shell, while keeping the same elementary or unit stress in the material thereof.

My invention is based on the property referred to, and provides a resistant submarine 30 hull or like elongated receptacle subjected to any external or internal pressure, as will be hereinafter described.

In the annexed drawings, Fig. 1 diagrammatically shows a side view of a resistant hull for submarines according to my invention, Figs. 2 to 7 inclusive are detail sectional views thereof, and Fig. 8 is an explanatory diagram.

As shown in Fig. 1 the submarine hull, 40 while not being shaped as a whole to a sphere, consists of a number of adjacent portions which embody the property that whatever cross section made by a plane—either at right angles or inclined to the axis of the hull—between any pair of adjacent web frames, substantially is a circle or an arc of circle having $R, R', \dots$ as the radius. In other words, any portion of plating between two 45 subsequent web frames is a spherical zone.

In any such zone the elementary stresses are throughout equal

$$55 \quad \frac{PR}{2},$$

and the material is throughout subjected only to compressive stresses due to the external hydrostatic pressure.

Should there be the matter of a receptacle 60 subjected to internal pressure (like by pressure-gas or pressure-liquid containers), it would only resist throughout to tensile stresses equal to

$$65 \quad \frac{PR}{2}.$$

In Fig. 1 the parallel end arrows F denote the axial thrust on the end plates of the hull, or like bottoms of any other elongated receptacle; $R, R', \dots$ denote the radii of the several portions, and O are web frames or circular ribs to strengthen the structure and to attach the spherical plating portions thereto.

In Figs. 2 to 7 inclusive I have shown by way of example different shapes of rolled irons O and arrangements of the plating in connection therewith.

As shown, the frame irons are preferably T-irons or bulb rails which may totally be enclosed internally of the plating (Figs. 2 and 4), or have the flange internally thereof and the web projecting externally therefrom (Figs. 3 and 5), while having the flange flat (Figs. 2 and 3) or angular in cross section (Figs. 4 and 5). Composite frame irons may also be used (Figs. 6 and 7), by arranging a bulb rail outside of the plating and providing a supplemental flat iron (Fig. 6) or an angle iron (Fig. 7) opposite the flange of the web iron, and preferably enclosing the platings therebetween. Of course, the bulb rail may be arranged inside and the supplemental iron outside of the plating.

In Fig. 8 I have shown the decomposition of the force

$$95 \quad \frac{PR}{2},$$

100 taken as the stress in a point of the peripheral

intersection of two adjacent spherical zones. The component A of said force, contained in an axial plane and parallel to the axis of the container, is resisted by the axial thrusts F (Fig. 1) on the end plates or bottoms, while the radial component B of said force, at right angles to the axis of the container, is resisted by the compressive strength of the web frames or ribs O.

10 A shell as described, either as the resistant hull of a submarine or as the longitudinal wall of any elongated receptacle generally, has the advantage that the material thereof may be made to work throughout uniformly.

15 What I claim is:

1. A rigid circumferentially corrugated container of circular cross section, comprising a shell made of adjacent nonresilient spherical undivided sections, the centers of said 20 sections lying on the longitudinal axis of the container, and circular cross frames stiffening said spherical sections at the points where they unite.

2. A submarine hull of circular cross section capable of resisting external and internal pressure, comprising a shell made of rigid plate in undivided sections in the form of spherical zones connected at their ends, and spaced circular stiffening frames for said 30 plate sections located at the planes where said sections interfere or connect.

3. A submarine hull of circular cross section capable of resisting external and internal pressure comprising longitudinally spaced 35 circular frames parallel to each other and at right angles to the axis of the hull, and a hull plating consisting of connected undivided sections in the form of spherical zones, said frames being attached thereto at the 40 points of connection of said zones.

4. A shell or casing including connected spherical zones composed of non-resilient material arranged end to end and provided with circular reinforcements between and at the 45 points of connection of said zones to adapt them to resist both inside and outside pressure.

In testimony whereof, I set my hand at
50 Genoa, Italy, this 2nd day of September,
1927.

ROBERTO GALEAZZI.
